INTERMEDIATE AMPLITUDE SIGNAL SELECTOR

BACKGROUND OF THE INVENTION

1. Field of the Invention

This invention relates to a signal selector and, more particularly, to an intermediate amplitude signal selector.

2. Description of the Prior Art

Heretofore, signal selectors of the type disclosed in U.S. Pat. No. 3,311,837 issued to Harold Moreines and in U.S. application Ser. No. 596,994 by Harold Moreines, the inventor of the present invention, select an intermediate amplitude signal from a group of three signals. The Moreines' patent and application are assigned to The Bendix Corporation, assignee of the present invention.

The present invention differs from the Moreines patent and application in that it is capable of selecting a particular signal from a group of four or more signals while the prior art can only select a median amplitude signal of three signals. The Moreines patent and application does not suggest that a particular signal can be selected from a group of four or more signals, much less the manner of combining inputs to achieve the selection of the particular signal.

SUMMARY OF THE INVENTION

An intermediate amplitude signal selector for selecting the rth ranking signal from m applied signals where m is greater than four and r is the rank in amplitude, comprising a plurality of selective gating circuits, each receiving a different group of signals less than m , for selecting an extreme signal in one sense of each group and providing at their outputs signals corresponding thereto. A gating network is connected to the outputs of the selective gating circuits and receives the signals therefrom and passes only the extreme signal of opposite sense which corresponds to the rth ranking signal. One object of the present invention is to select one signal from a group of four or more signals as determined by the amplitudes of the signals.

Another object of the present invention is to use a minimum number of gating circuits for the selection of a particular signal from a group of signals.

Another object of the invention is to select an extreme signal of one sense (either the least positive or most positive amplitude signal) from groups of signals and then selecting an extreme signal of opposite sense (either the most positive or least positive amplitude signal) from the selected signals to eliminate all but the rth ranking signal.

The foregoing and other objects and advantages of the invention will appear more fully hereinafter from a consideration of the detailed description which follows, taken together with the accompanying drawings wherein two embodiments of the invention are illustrated by way of example. It is to be expressly understood, however, that the drawings are for illustration purposes only and are not to be construed as defining the limits of the invention.

DESCRIPTION OF THE DRAWINGS

FIG. 1 shows a novel signal selector constructed in accordance with the present invention for selecting a third most positive direct current signal from a group of five direct current signals.

FIGS. 2 and 3 are schematic diagrams of the least positive signal selector and the most positive signal selector, respectively, shown in FIG. 1.

FIG. 4 is another novel signal selector constructed in accordance with the present invention for selecting the third most positive direct current signal from a group of five signals.

DESCRIPTION OF THE INVENTION

Referring to FIG. 1, there is shown an intermediate signal selector for selecting the third ranked signal with respect to the most positive signal, from a group of five signals and having terminals 2, 2A, 2B, 2C and 2D receiving signals E_1 , E_2 , E_3 , E_4 , and E_5 respectively. For purposes of explanation only, it is

assumed that $E_1 \geq E_2 \geq E_3 \geq E_4 \geq E_5$. Least positive signal selectors 7 through 7I, which may be of the type shown in detail in FIG. 2, are connected to terminals 2 through 2D so that each least positive signal selector receives a different combination of three signals. A least positive signal selector provides a signal corresponding to the applied signal having the least positive amplitude as hereinafter explained.

Selectors 7 through 7I provide signals E_7 through E_{7I} , respectively, which are applied to a most positive signal selector 10, which may be of the type shown in detail in FIG. 3. A most positive signal selector provides a signal corresponding to the most positive applied signal. Most positive selector 10 provides a signal E_{10} corresponding to the third most positive signal in response to signals E_7 through E_{7I} .

When signals E_1 through E_5 are direct current signals, signals E_7 through E_{7I} are direct current signals. Signal E_7 corresponds to signal E_3 , signals E_{7A}, E_{7C}, E_{7F} , correspond to signal E_4 , and signal $E_{7B}, E_{7D}, E_{7E}, E_{7G}, E_{7H}$ and E_{7I} corresponds to signal E_5 . Since signal E_4 is more positive than signals E_4 or E_5 , signal E_{10} corresponds to signal E_3 .

When signals E_1 through E_5 are in phase alternating current signals, signals E_7 through E_{7I} are in phase alternating current signals. During positive half-cycles, signal E_7 corresponds to signal E_3 ; signals E_{7A}, E_{7C}, E_{7E} correspond to signal E_4 ; and signals $E_{7B}, E_{7D}, E_{7E}, E_{7G}, E_{7H}$ and E_{7I} correspond to signal E_5 . During negative half-cycles, signals E_7 through E_{7I} correspond to signal E_1 ; signals E_{7F} through E_{7H} correspond to signal E_2 and signal E_{7I} corresponds to signal E_3 . During the positive half-cycles of signal E_7 through E_{7I} , the most positive signal is E_7 , while during the negative half-cycles the most positive signal is E_{7I} so that signal E_{10} from most positive signal selector corresponds to signal E_3 .

A source 11 of fixed direct current voltages provides a positive direct current voltage E_{11} to least amplitude signal selectors 7 through 7I and a negative direct current voltage E_{11A} to most positive signal selector 10 to bias the signal selectors.

Referring to FIG. 2, there is shown least positive signal selector 5 having diodes 13, 13A and 13B clamping positive direct current voltage E_{11} to the level of the least positive signal applied to the diodes. Signals E_1 , E_2 , and E_3 are applied to the cathodes of diodes 13, 13A and 13B respectively, while voltage E_{11} is applied through a biasing resistor 15 to common connected anodes of the diodes.

Referring to FIG. 3, there is shown most positive signal selector 10 having diodes 17 through 17I having common connected cathodes and clamping negative direct current voltage E_{11A} to the level of the most positive signal applied to the diodes to provide signal E_{10} . Signals 17 through 17I are applied to anodes of diodes 17 through 17I, respectively, while voltage E_{11A} is applied through a biasing resistor 19 to the cathodes of the diodes.

Another embodiment of the present invention for selecting the third ranked signal from a group of five signals is shown in FIG. 4, in which most positive signal selectors 21 through 21I are connected to terminals 23, 23A, 23B, 23C and 23D, receiving signals E_1 , E_2 , E_3 , E_4 and E_5 , respectively, so that each most positive signal selector receives a different combination of three signals. Most positive signal selectors 21 through 21I are constructed and operate in a manner similar to most positive signal selector 10. Most positive signal selectors 21 through 21I apply signals E_{21} through E_{21I} , respectively, to a least positive signal selector 25. Least positive signal selector 25 is constructed and operates in a manner similar to least positive signal selector 5 to provide a signal E_{25} corresponding to the third most positive signal E_3 .

When signals E_1 through E_5 are direct current signals, signals E_{21} through E_{21I} are direct current signals. Signals E_{21} through E_{21I} correspond to signal E_1 , signals $E_{21F}, E_{21G}, E_{21H}$ corresponds to signal E_2 . Since signal E_3 is less positive than signals E_1 and E_2 , signal E_{25} corresponds to signal E_3 .

When signals E_1 through E_5 are in phase alternating current signals, signals E_{21} through E_{21I} are also in phase alternating current signals. During positive half-cycles, signals E_{21} through

E_{21E} correspond to signal E_1 , signals E_{21F} , E_{21G} , E_{21H} correspond to signal E_2 , and signal E_{21I} corresponds to signal E_3 . During negative half-cycles, signal E_{21I} corresponds to signal E_3 , signals E_{21A} , E_{21C} , E_{21F} correspond to signal E_4 and signals E_{21B} , E_{21D} , E_{21E} , E_{21G} , E_{21H} and E_{21I} correspond to signal E_5 . During the positive half-cycles signal E_{21I} is the least positive while during the negative half cycle signal E_{21I} is the least positive so that signal E_{21S} corresponds to signal E_5 .

A source 26 of fixed direct current voltages applies a negative direct current voltage E_{26} to most positive signal selectors 21 through 211 and a positive direct current voltage E_{26A} to least positive signal selector 25 to bias the signal selectors.

While the arrangement shown and described in FIGS. 1 and 4 select the third ranked signal from a group of five signals, the arrangement may be used for selecting any intermediate signal from any number of signals. An intermediate amplitude signal selector for selecting an rth ranking from m applied signals may be constructed similar to the signal selector shown in FIG. 1 using N number of least positive signal selectors as determined by the following equation:

$$N = (m! / r! (m-r)!) \quad \text{The signals are applied to the least positive signal selectors in different combinations of } r \text{ number of signals.}$$

Another type of intermediate amplitude signal selector may also be constructed similar to that shown in FIG. 4 using N number of most positive signal selectors as determined by the following equation:

$$N = (m! / (m-r+1)! (r-1)!) \quad \text{where } m \text{ is the number of applied signals and } r \text{ is the ranking of the selected signal with respect to the most positive signal. The signals are applied to the most positive signal selectors in different combination of } (m-r) \text{ number of inputs.}$$

When an alternating current signal, which is not the median ranked signal, is to be selected from a group of in phase alternating current signals and is applied to a signal selector of the type shown in FIG. 1, the positive direct current voltage E_{11} from source 11 is replaced by a square wave voltage in phase with the alternating current signals. The square wave voltage effectively gates the least positive signal selectors so that each selector passes only the positive half-cycles of the least positive signal. Preferably the signal from the most positive signal selector is then applied to either a high-pass filter to provide an alternating current signal as the selected signal or to a low-pass filter to provide a direct current signal corresponding to the selected signal.

Similarly, a square wave voltage 180° out of phase with the alternating current signals replaces direct current voltage E_{28} from source 26 and is applied to the most positive signal selectors of a signal selector of the type shown in FIG. 4 so that a nonmedian signal may be selected from a group of alternating current signals having the same phase. Each most positive signal selector passes positive half-cycles of the most positive applied signal. It is preferred that the signal from the least positive signal selector be applied to either a high pass filter to provide an alternating current signal as the selected signal or to a low pass filter to provide a direct current signal corresponding to the selected signal.

The present invention as heretofore described uses a minimum number of gating circuits to select one signal from a group of at least five signals as determined by the amplitudes of the signals. The present invention selects an extreme signal of one sense (either the most positive or least positive amplitude signal) from groups of signals and then select an extreme signal of opposite sense (either the least positive or most positive amplitude signal) from the selected signals to eliminate all but the rth ranking signal.

It will be obvious that either the least positive or most positive amplitude signal of each group is selected by the least positive signal selector 7 or the most positive signal selector 21 and the associated most positive signal selector 10 or least positive signal selector 25 is used to select the most positive or

the least positive amplitude signal. This arrangement using the number of selectors in accordance with equation 1 and 2 will eliminate all signals except the rth ranking signal.

While several embodiments of the invention have been illustrated and described in detail, it is to be expressly understood that the invention is not limited thereto. Various changes may also be made in the design and arrangement of the parts without departing from the spirit and scope of the invention as the same will now be understood by those skilled in the art.

What is claimed is:

1. An intermediate amplitude signal selector for selecting the rth ranking signal from m applied signals where m is greater than three and r gating the rank in amplitude, comprising a plurality of selective gating circuits, each receiving a different group of signals less than m , for selecting an extreme signal in one sense of each group and providing at their outputs signals corresponding thereto, and a gating network connected to the outputs of the selective gating circuits and receiving the signals therefrom and passing only the extreme signal of opposite sense which corresponds to the rth ranking signal.
2. An intermediate amplitude signal selector of the kind described in claim 1 in which each selective gating circuit has means for selecting the signal of the group having the least positive amplitude, and the gating network has means for selecting the most positive signal and providing a signal corresponding to the rth signal.
3. An intermediate amplitude signal selector of the kind described in claim 2 in which the number N of least positive signal selecting means corresponds to the number m of applied signals and to the rth ranking signal to be selected in accordance with the expression $N = (m! / r! (m-r)!)$, and the number of inputs to each least positive signals selector equals r .
4. An intermediate amplitude signal selector of the kind described in claim 2 in which least positive signal selecting means includes a plurality of diodes to which the signals are applied, biasing means connected to the diodes, and an output connected to the diodes and to the biasing means for providing the signal corresponding to the least positive signal.
5. An intermediate amplitude signal selector of the kind described in claim 2 in which the most positive signal selecting means includes a plurality of diodes to which the signals from the least positive signal selecting means are applied, and an output connected to the diodes and to the biasing means for passing the most positive signal.
6. An intermediate signal selector of the kind described in claim 1 in which each selective gating circuit has means for selecting the signal corresponding to the signal of the group having the most positive amplitude, and the gating network has means for selecting the least positive signal and provides a signal corresponding to the rth signal.
7. An intermediate amplitude signal selector of the kind described in claim 6 in which the number N of most positive signal selecting means corresponds to the number m of applied signals and to the rth ranking signal to be selected in accordance with the expression $N = (m! / (m-r+1)! (r-1)!)$ and the number of inputs to each most positive signal selecting means equals $(m-r+1)$.
8. An intermediate amplitude signal selector of the kind described in claim 6 in which each most positive signal selecting means includes a plurality of diodes to which the signals are applied, biasing means connected to the diodes, and an output connected to the diodes and to the biasing means for providing the signal corresponding to the most positive signal.
9. An intermediate amplitude signal selector of the kind described in claim 6 in which the least positive signal selecting means includes a plurality of diodes to which the signals from the most positive selecting means are applied, and an output connected to the diodes and to biasing means for passing the least positive signal.
